ABSTRACT OF THE DISCLOSURE

A traveling wave type electron tube, for extremely high frequencies, provided with a comb-type slow wave circuit. The electron tube includes a wave energy absorbing attenuator provided at one end of the slow wave circuit on the collector electrode side. The comb-type circuit is arranged so that the depth of the comb teeth gradually decreases at the end towards the electron gun and it is coupled to a ridge waveguide contiguous therewith and composed of a ridge, which has the same transverse width as the comb-type circuit, directed towards the bottom of the comb so that an electromagnetic wave is introduced into a fold-back waveguide from the fore end of the ridge waveguide to the collector electrode side. Furthermore, this electron tube includes an airtight connection window provided at the output end thereof. Such an arrangement makes the device compact and can eliminate reflection of waves in the discontinuous portion of the waveguide and thus provide a good matching characteristic with a constant output of a wide frequency range.

This invention relates to extremely high frequency electron tubes, and has for its object to provide tubes particularly adapted for industrial mass production.

There have been proposed and devised various types of electron tubes for amplifying or generating extremely high frequency signals. Among them are electron tubes for treating signals of a few-millimeters in wavelength which are considered useful, if they utilize the interaction between an electromagnetic wave on a comb type circuit and an electron beam.

In general, a comb type circuit is known as a slow wave circuit of such a construction that a number of lateral slots are cut into the ridge of a ridge waveguide, with a constant period, and the ridge is grooved or perforated longitudinally for passing an electron beam therethrough. In a comb type backward wave tube or a comb type traveling wave tube employing a comb type circuit, the tube is usually of slender and long construction in view of the arrangement of the electron-beam focusing apparatus, the electron beam being passed centrally in the axial direction, and the input and output transmission lines are formed by use of rectangular waveguides.

However, any of the extremely high frequency electron tubes heretofore proposed with utilization of comb type circuits has not been of a construction adapted for industrial mass production nor of a convenient shape for practical use. Thus, for example, a comb type circuit is a slow wave circuit surrounded by a metal wall and an extremely high geometrical correctness is required with respect to the central axis of the electron-beam groove or hole. Consequently, in the electron gun side of such an electron tube, a special construction and dimensional precision are required for the couplings between input and output waveguides and the comb type circuit. For satisfying the above requirements in old electron tubes employing comb

2

type circuits, troublesome and time-consuming mechanical devices have been required for cutting out from a single metal block an integral body composed of the comb portion and surrounding walls of complicated configurations.

Conventional input and output couplings heretofore used are rectangular waveguide systems in which the waveguide openings are disposed in a broad wall face in opposition to the comb teeth, namely the upper wall of the comb type circuit at the opposite ends thereof and the axes of the input and output waveguides at the openings are perpendicular to the electron beam axis. In the case when the windows of the input and output waveguides are disposed at the side of the collector electrode, the waveguides are bent in the respective directions between coupling portions and the tube envelope by 90 degrees and directed to the collector electrode side. In such a conventional construction, however, mode conversion of the electromagnetic wave is effected abruptly at the coupling portion from the comb type circuit to the waveguide, and there being a resonance circuit included in the coupling portion in many cases, good matching characteristics cannot be obtained in a broad frequency band. In addition, the comb portion and the rectangular waveguide portion have been manufactured separately. It has been difficult to keep precision in assembly, resulting in a narrow frequency band in which good matching is possible. Further, the core portion of the electron tube is of peculiar form and large size so that it is not suitable for practical use.

The present invention provides an extremely high frequency (EHF) electron tube adapted for practical use, that can solve the various problems described above.

An additional object of the present invention is to provide an EHF electron tube having a small reflection and a small loss over a broad frequency band.

Another object of the invention is to provide an electron tube having good characteristics over a broad frequency band, with a high yield rate in industrial production and adaptability for mass production with respect

to construction.

A further object of the invention is to provide an EHF electron tube of short dimension, yet with good characteristics over a broad frequency band.

There are other objects and particularities of the present invention, which will be made obvious from the following detailed description, with reference to the accompanying drawings, in which:

FIGS. 1 and 2 show a backward wave oscillator tube embodying the present invention, in cross section and longitudinal section, respectively;

FIG. 3 shows a process of manufacturing the combined comb teeth and ridge in the embodiment shown in FIGS. 1 and 2;

FIG. 4 is a detailed perspective sectional view of a portion of FIG. 2, with representation of various dimensions;

FIGS. 5 and 6 are graphs showing performances of the electron tubes shown in FIGS. 1 to 4;

FIG. 7 shows the detailed construction of a part shown in FIG. 2;

FIG. 8 is a sectional view taken at line A-A' in FIG. 7;

FIGS. 9 and 10 are graphs showing performances of the electron tube of the invention;

FIG. 11 shows a modified form of the tube shown in FIGS. 1 and 2;

FIG. 12 is a longitudinal sectional view of a traveling wave amplifier tube embodying the invention; and

FIG. 13 is a cross-sectional view of another embodiment of the invention.

Referring now to FIGS. 1 and 2, the backward wave tube illustrated comprises a metal strip 1 of a thickness

equal to the lateral width of comb teeth k , a and b formed on the upper longitudinal side of the strip along the effective length of the same. At the end portion of the strip near the electron gun, between the teeth b and corner c , several lateral slots gradually diminishing towards the corner are provided in order to lessen reflection of the electromagnetic wave, while at the other end portion near to the collector electrode 10, that is near to the teeth k , the teeth have gradually decreasing height in order to lessen the electromagnetic wave reflection. At the side near to the collector electrode 10, on the lower longitudinal side of the strip 1, there is formed a tapered portion x for converting a ridge waveguide to a rectangular waveguide. A pair of opposite symmetrical metal members 2 and 3 are provided in close contact with the metal strip 1, forming the opposite side walls of the comb type circuit at their upper portions, and the opposite side walls of the ridge waveguide at their side and lower portions. The wall-to-teeth spacing l_1 , wall-to-ridge spacing l_3 at the vertical side, and wall-to-ridge spacing l_2 at the lower longitudinal side are kept to predetermined values by brazing or otherwise fastening metal members 2 and 3 to the metal strip 1 with precise positional relations. The upper wall of the comb type circuit is formed by a metal member 4. The composite part consisting of members 1, 2 and 3 is enclosed in a metal member 5 of a channel-shape cross section, members 4 and 5 being fixed together by a suitable number of set screws.

A pair of opposite supporter metal plates 6 and 7 are provided with a central electron-beam slit 14 and a central port 15 for an attenuator, respectively, and have peripheral shapes fitting the inside wall of the cylindrical envelope 8 of the tube.

The combination of the above-described members 1 through 7 constitutes a structure having a comb type circuit k , a , b at the upper portion, a ridge waveguide $c-d$ at the side portion, and a ridge waveguide $d-e$ and a taper-ridge waveguide $e-f$ at lower portion, and is inserted in the cylindrical envelope 8. For taking out the output, a rectangular waveguide 9 is provided passing through the collector electrode 10 and having a passage h in continuation with a rectangular port g of the metal plate 7 and the taper-ridge waveguide $e-f$. The collector electrode 10 is provided with a collector hole 11. In the opposite end portion of envelope 8, an electron gun 12 is mounted for generation of an electron beam 13.

The electron beam 12 interacts with the high-frequency electric field on the comb type circuit, under an appropriate accelerating voltage in the well-known manner, and the generated electromagnetic wave is transmitted by way of $a \rightarrow b \rightarrow c \rightarrow d \rightarrow e \rightarrow f \rightarrow g \rightarrow h$ and a dielectric disk 33 to a rectangular waveguide outside the electron tube. Here, the portion $b-c$ is the conversion portion from the comb type circuit to the ridge waveguide, the portion $c-d$ is the vertical ridge waveguide, the portion $d-e$ is the fold-back ridge waveguide, the portion $e-f$ is the conversion portion from the ridge waveguide to the rectangular waveguide, the portion $g-h$ is the rectangular waveguide, and the portions c and d are corners of the ridge waveguides. The angle of bent corner c is 90 degrees, while that of corner d may be a right angle or an obtuse angle. Instead, there may be employed a bent ridge waveguide at the corner d .

According to the invention, the ridge of the ridge waveguide, directed to the bottom of the slots of the comb type circuit at the electron-gun side of the comb type circuit, and the ridge of the fold-back waveguide, as well as the comb teeth, are formed as one body from a single metal strip, whereby reflection of the electromagnetic wave is negligibly small, and good matching characteristics are obtained with a constant output over a wide frequency band. Further, by use of the single strip, as above-described with one longitudinal side provided with comb teeth and one lateral side and the other longitudinal side forming ridges, the passage of an electro-magnetic wave

can be bent into a reclined-U-shape, so that the whole structure may be accommodated within a cylindrical envelope in a compact form of extremely practical usage.

Referring to FIG. 3, eight metal strips 1 are fixed as one body in lateral alignment between a holding wall 21 of a mount base 20 and a holding plate 22. By rotating the cutter 23 mounted on a shaft 24 supported in a bearing 25 being mechanically reciprocated in the directions of arrows shown the lateral slots 26 may be provided in the metal strips 1. According to the invention, a number of metal strips 1 may be subjected to mechanical working at the same time, as above-mentioned, obviating the relatively long period of time required by ordinary individual machining. Consequently, precise and efficient cutting is possible by the above-mentioned simultaneous machining.

The connection between the waveguide 9 and the external waveguide 30 shown in the right-hand portion of FIG. 2 is now to be explained. This connection is designed substantially for the elimination of reflection and loss of the electromagnetic wave over the whole frequency band used in the rectangular waveguide, while assuring easy sealing between the dielectric disk and the metal parts in the hermetic window construction of the waveguide for an electron tube of the millimeter wave region.

Referring to FIGS. 2 and 4, a thin cylindrical space 31 is formed in an end flange 35 of the rectangular waveguide 9, and has a thickness W which is small in comparison to its diameter D_0 . The flange 35 is made of iron-nickel-cobalt alloy, or copper, etc., and is provided with an annular angular cut 34 around the cylindrical space 31 in the butt face 32 of flange 35, for receiving a dielectric disk 33 of diameter D_1 at a right angle to the axis of waveguide 9, in a sealing condition. The dielectric disk 33 is made of glass, ceramics, sapphire, quartz or the like, and is positively sealed to the flange 35 in the annular angular cut 34 by means of glazing, brazing, or other appropriate means depending upon the dielectric material used. The external waveguide 30, in axial alignment with the waveguide 9, has an end flange 36 having a thin cylindrical space 37 of the same dimensions as the space 31 and in register with the latter. By such a construction, the dielectric disk 33 can be positively sealed to the flange 35 along the peripheral face having width t , as well as, the annular edge portion of the disk plane having a radial width of $\frac{1}{2}(D_1-D_0)$. There might occur certain disturbance of the electromagnetic field by virtue of the existence of the annular angular cut 34 of $\frac{1}{2}(D_1-D_0)$ radial width, but such a disturbance does not affect the transmission characteristics disadvantageously, if the thickness W and diameter D_0 of the spaces 31 and 37 are selected in an appropriate dimensional relation, and good transmission characteristics can be obtained over a broad frequency band.

Thus, referring to FIG. 4, it has been found that if the thickness t and specific dielectric constant ϵ of the dielectric disk 33 and the internal lateral widths α of waveguides 9 and 30 are selected in the range of $0.15 \alpha < \epsilon t < 0.5\alpha$, and the diameter D_0 and thickness W of the spaces 31 and 37, and the diameter D_1 of the dielectric disk 33 are selected in the ranges of $0.7\alpha < D_0 < 1.0\alpha$, $0.05\alpha < W < 0.25\alpha$, and $0.1\alpha < (D_1-D_0) < 0.3\alpha$, then the electric field component of the transmitted electromagnetic wave is distributed to become substantially perpendicular to the plane of dielectric disk 33, and the voltage standing wave ratio (VSWR) and the transmission loss are sufficiently decreased over the whole frequency band used in the rectangular waveguides 9 and 30.

Further, with the construction of the above embodiment of the invention, when the dielectric disk 33 is glass-sealed or brazed to the flange 35, the sealing is effected along a portion of the flat disk plane, but not the peripheral face, so that the disk may be held pressed to the face of the annular angular cut 34, that is, perpendicular to the axis of the waveguide, and yet there can exist a length of $\frac{1}{2}(D_1-D_0) + t$ between the vacuum region and ambient air region at both sides of the sealing portion. Consequent-

ly, in comparison to a conventional hermetic window inserted in a choke-flange connection, positive and good hermetic sealing can be accomplished. Tests show that a superior voltage standing wave ratio and transmission loss are obtained as shown in FIGS. 5 and 6 with the new connecting construction. In these tests, the connecting construction had the following dimensions:

$$\begin{aligned}\alpha &= 22.9 \text{ millimeters}, \\ D_0 &= 0.96\alpha, \\ D_1 - D_0 &= 0.175\alpha, \\ W &= 0.196\alpha, \\ \epsilon \times t &\doteq 0.32\alpha.\end{aligned}$$

As seen from these figures of drawings, within the frequency range from 8.2 gigacycles to 12.4 gigacycles, the voltage standing wave ratio is lower than 1.14 (FIG. 5) and the transmission loss is lower than 0.4 decibel (FIG. 6). Such extremely superior characteristics can be obtained in any region of extremely high frequency by virtue of the law of similarity of electromagnetic waves. The new connecting construction is extremely simple and easy to manufacture and is adapted for industrial mass production.

The construction of the central port 15 for the attenuator in the supporter metal plate 7 will now be described in detail with reference to FIGS. 7 and 8.

The comb teeth of the comb type circuit decrease in height gradually near to k at the collector-electrode end of teeth a , and at the end of metal member 4 the circuit is converted to a rectangular waveguide 40. The supporter metal plate 7 between the waveguide 40 and the collector hole 11 is provided with a short cylindrical port 15 passing therethrough and having a diameter D_a larger than the lateral width α of rectangular waveguide 40, the axis of port 15 being in coincidence with the axis of waveguide 40. Within the cylindrical port 15, one or more dielectric plates 42, of small thickness T_a in comparison to the wavelength of the electromagnetic wave under consideration and covered by films 41 of resistance material, are arranged in parallel to the narrower wall of the rectangular waveguide 40, the edges of the plates 42 being fixed to the plate 7 in grooves 43 formed therein by glass-sealing, brazing, or simple insertion. The collector hole 11 formed in the collector electrode 10 is of a pore form of a diameter E_a sufficient to contain the cross-sectional area of electron beam 13 so that feedback of the secondary electron may be prevented.

With the above-mentioned construction, the forward progressive wave directed to the collector electrode, which is a component of the electro-magnetic wave generated in the comb type circuit that is not necessary for the backward wave oscillator tube, is after introduction into the cylindrical port 15, divided into two components that proceed in the upward and downward directions, respectively, as shown by chain lines 44 in FIG. 7, their electric field components being distributed as shown by arrowed lines 45 so that the resistance films 41 act effectively to damp the energy of the forward progressive wave. FIG. 9 shows the relation between frequency and the voltage standing wave ratio as measured from the side of the rectangular waveguide 40. In the measurements, two dielectric plates 42 were employed with the following constructional dimensions:

$$\begin{aligned}\beta &\doteq 0.45\alpha, \\ D_a &\doteq 1.8\alpha, \\ C_a &\doteq 0.87\alpha, \\ X_a &\doteq 0.75\alpha, \\ T_a &\doteq 0.09\alpha,\end{aligned}$$

dimensions β , D_a , C_a , X_a and T_a being as illustrated in FIGS. 7 and 8 and the specific dielectric constant $\epsilon_a \doteq 5$. In FIG. 9, the abscissa shows the frequency normalized by the lower cutoff frequency f_{lc} of the rectangular waveguide, that is, f/f_{lc} , and their opposite ends substantially

correspond to the normal range of use of the rectangular waveguide.

As is clearly seen from FIG. 9, in the attenuator of the above construction the voltage standing wave ratio is below 1.1 over the substantial portion of the frequency band used in the rectangular waveguide, and it is suitable as the terminating attenuator for a slow wave circuit of a backward wave oscillator tube by reason of its broad operating frequency range.

This attenuator can also be of short dimension in the longitudinal direction of a slow wave circuit, is easy to manufacture by reason of its simple construction, and consequently, is very useful from the industrial view point as an attenuator for the termination of a slow wave circuit.

In FIG. 10 there is shown the whole performance, as measured at an outer flange of the waveguide 30, of the extremely high-frequency backward wave oscillator as shown in FIGS. 1 and 2. In the construction shown therein, wall-to-teeth spacing l_1 , and wall-to-ridge spacing l_2 , l_3 are all equal, and $l_1 = l_2 = l_3 = 0.2$ millimeter. The heights of the comb type circuit in the direction of A-A' and ridge waveguide are 1.2 millimeters and 1.55 millimeters, respectively; the lateral widths of the upper wall of the comb type circuit and ridge waveguides are 3.1 mm., respectively; the length of the shorter side of metal strip 1 is $m = 8$ millimeters; and the lateral widths of comb teeth and ridges are $n = 1.05$ millimeters. The frequency band ranges from 55 gc. to 77 gc. In FIG. 10, the abscissa shows f/f_{lc} , the frequency normalized by the upper cut-off frequency of the comb type circuit $f_{lc} = 82$ gc., while the ordinate shows voltage standing wave ratio (VSWR). As is clear from FIG. 10, the VSWR of the present embodiment of the invention is sufficiently low and satisfactory as a backward wave tube.

In the modification shown in FIG. 11, a short ridge waveguide $d-d'$ is inserted between the vertical ridge waveguide $c-d$, perpendicular to the electron beam axis at the end near to the electron gun, and the fold-back ridge waveguide $d'-e'-f$ and the waveguide $d-d'$ has an inclination intermediate both waveguides $c-d$ and $d'-e'-f$. In addition, the fold-back waveguide $d'-e'-f$ is a long and gentle taper-ridge waveguide and is converted to a rectangular waveguide at the output end f . By utilization of the slanted ridge waveguide $d-d'$ and the long and gentle taper ridge waveguide $d'-e'-f$ the transmission characteristics have been greatly improved.

In FIG. 12 there is shown a traveling wave amplifier tube embodying the invention. The construction of this embodiment is similar in general to the backward wave oscillator tube shown in FIGS. 1 and 2, and the description will be given below only on the parts different from the latter. Contrary to the case of FIG. 2, the input electromagnetic wave is introduced through a rectangular waveguide 9 and proceeds by way of $h \rightarrow g \rightarrow g \rightarrow f \rightarrow e \rightarrow d \rightarrow c \rightarrow b \rightarrow a$ while, under interaction with the electron beam, the wave is amplified and the amplified output is transmitted by way of $k \rightarrow q \rightarrow r \rightarrow s$ to an output waveguide 16 from which the output is taken.

It will readily be understood that a traveling wave amplifier and a backward wave amplifier may be of one and the same construction, provided that the operational conditions are converted from each other, the only difference therebetween being that the directions of input and output are reversed from each other. Thus, a backward wave amplifier tube can be obtained by use of the construction shown in FIG. 12.

FIG. 13 shows a still further embodiment of the invention, in which the comb-teeth portion of metal strip 1 is provided with a through hole 102 for transmission of an electron beam, instead of a longitudinal groove 103 in the embodiment shown in FIGS. 1 and 2. The operation of the present embodiment is substantially the same with that of FIGS. 1 and 2.

What we claim is:

What we claim is:

1. An extremely high frequency electron tube of the traveling wave type comprising a substantially cylindrical enclosure having at one end thereof an electron gun and at the opposite end thereof a collector electrode arranged in alignment with said electron gun, a comb-type circuit formed on a ridge in a first ridge waveguide, said ridge of said first ridge waveguide being a metal strip having a plurality of transverse slots therein thereby forming comb teeth, said comb-type circuit being mounted in said cylinder between said electron gun and said collector electrode along the path of travel of the electron beam from said gun, said comb teeth being gradually diminished in height at the end of said circuit towards said electron gun, a second ridge waveguide transversely mounted in said cylinder directed towards the bottom of said comb teeth and being continuous therewith, said second ridge having the same transverse width as said comb teeth, and a fold-back waveguide directed towards the collector electrode and connected to the fore end of said second ridge waveguide, said fold-back waveguide including a tapered portion.

2. The electron tube according to claim 1, in which the main portion of said fold-back waveguide is a third ridge waveguide having a ridge in continuation with the ridge of the second ridge waveguide.

3. The electron tube according to claim 1, in which the main portion of said fold-back waveguide is a third ridge waveguide having a ridge in continuation with the ridge of the second ridge waveguide and is constituted by butting two metal members, upon both sides of said metal strip having comb teeth, said members having faces defining the bottom wall of said first ridge waveguide and forming the ridge after assembly.

4. The electron tube according to claim 1, in which a short cylindrical port surrounded by a conductor is connected to a rectangular waveguide at the collector electrode side of said comb type circuit, said port having a diameter larger than the lateral width of said rectangular waveguide and an axis in coincidence with the axis of said rectangular waveguide, at least one dielectric plate mounted within said cylindrical port, said plate being covered with films of resistance material attached on its surfaces and having a small thickness in comparison to the wavelength of the electromagnetic wave of said rectangular waveguide, and being in parallel with the shorter wall of said rectangular waveguide, thus constituting a backward wave oscillator.

5. The electron tube according to claim 1, in which the main portion of said fold-back waveguide is a third ridge waveguide having a ridge in continuation with the ridge of the second ridge waveguide and in which a short cylindrical port surrounded by a conductor is connected to a rectangular waveguide at the collector electrode side of said comb type circuit, said port having a diameter larger than the lateral width of said rectangular waveguide and an axis in coincidence with the axis of said rectangular waveguide, at least one dielectric plate mounted in said cylindrical port, said plate being covered with films of resistance material attached on its surfaces and having a small thickness in comparison to the wavelength of the electromagnetic wave of said rectangular waveguide, and being in parallel with the shorter wall of said rectangular waveguide, thus constituting a backward wave oscillator.

6. The electron tube according to claim 1, in which the main portion of said fold-back waveguide is a third ridge waveguide having a ridge in continuation with the ridge of the second ridge waveguide and is constituted by butting two metal members upon both sides of the metal strip having comb teeth at the essential portion said metal members having faces defining the bottom wall of said first ridge waveguide and forming the ridge after assembly, a short cylindrical port surrounded by a conductor connected to a rectangular waveguide at the collector.

tor electrode side of said comb type circuit, said port having a diameter larger than the lateral width of said rectangular waveguide and an axis in coincidence with the axis of said rectangular waveguide, at least one dielectric plate mounted within said cylindrical port and being covered with films of resistance material attached on its surfaces and having a small thickness in comparison to the wavelength of the electromagnetic wave of said rectangular waveguide, and being in parallel with the shorter wall of said rectangular waveguide, thus constituting a backward wave oscillator.

7. The electron tube according to claim 1, in which the output end of said fold-back waveguide is converted to a rectangular waveguide, a thin cylindrical space 15 formed in an enclosure at the connecting portion between said rectangular waveguide and an external rectangular waveguide, said enclosure being composed of two parts with butt faces therebetween, an annular angular cut being formed in the butt face of the electron-tube side, and a 20 dielectric disk being placed in said annular angular cut perpendicular to the axis of said rectangular waveguides and sealed to said annular angular cut.

8. The electron tube according to claim 1, in which the main portion of said fold-back waveguide is a third ridge waveguide having a ridge in continuation with the ridge of the second ridge waveguide and in which the output end of said fold-back waveguide is converted to a rectangular waveguide, a thin cylindrical space formed in an enclosure at the connecting portion between said rectangular waveguide and an external rectangular waveguide, said enclosure being composed of two parts with butt faces therebetween, an annular angular cut being formed in the butt face of the electron-tube side, and a dielectric disk being placed in said annular angular cut, and perpendicular to the axis of said rectangular waveguides and sealed to said annular angular cut.

and sealed to said annular angular cut.

9. The electron tube according to claim 1, in which the main portion of said fold-back waveguide is a third ridge waveguide having a ridge in continuation with the ridge of the second ridge waveguide and constituted by butting two metal members upon both sides of the metal strip having comb teeth at the essential portion, said metal members having faces defining the bottom wall of said first ridge waveguide and forming the ridge after assembly,

40 45 the output end of said fold-back waveguide being converted to a rectangular waveguide, a thin cylindrical space formed in an enclosure at the connecting portion between said rectangular waveguide and an external rectangular waveguide, said enclosure being composed of two parts with butt faces therebetween, an annular angular cut being formed in the butt face of the electron-tube side, and a dielectric disk being placed in said annular angular cut perpendicular to the axis of said rectangular waveguides and sealed to said annular angular cut.

50 55

55 cut.

10. The electron tube according to claim 1, in which
the main portion of said fold-back waveguide is a third
ridge waveguide having a ridge in continuation with the
ridge of the second ridge waveguide and constituted by
60 butting two metal members upon both sides of the metal
strip having the comb teeth at the essential portion, said
metal members having faces defining the bottom wall of
said first ridge waveguide and forming the ridge after
assembly, the output end of said fold-back waveguide
65 being converted to a rectangular waveguide, a thin cylin-
drical space formed in an enclosure at the connecting
portion between said rectangular waveguide and an ex-
ternal rectangular waveguide, said enclosure being com-
posed of two parts with butt faces therebetween, an annu-
11 lar angular cut being formed in the butt face of the elec-
tron-tube side, and a dielectric disk being placed in said
11 annular angular cut perpendicular to the axis of said
11 rectangular waveguides and sealed to said annular angular
70 cut.

75 11. The electron tube according to claim 1, in which

the main portion of said fold-back waveguide is a third ridge waveguide having a ridge in continuation with the ridge of the second ridge waveguide, in which a short cylindrical port surrounded by a conductor is connected to a rectangular waveguide at the collector electrode side of said comb type circuit, said port having a diameter larger than the lateral width of said rectangular waveguide and an axis in coincidence with the axis of said rectangular waveguide, at least one dielectric plate mounted within said cylindrical port and covered with films of resistance material attached on its surfaces and having small thickness in comparison to the wavelength of the electromagnetic wave of said rectangular waveguide, and being in parallel with the shorter wall of said rectangular waveguide, thus constituting a backward wave oscillator, the output end of said fold-back waveguide being converted to a rectangular waveguide, a thin cylindrical space formed in an enclosure at the connecting portion between said rectangular waveguide and an ext-

5 nal rectangular waveguide, said enclosure being composed of two parts with butt faces therebetween, an annular angular cut being formed in the butt face of the electron-tube side, and a dielectric disk being placed in said annular angular cut perpendicular to the axis of said rectangular waveguides and sealed to said annular angular cut.
